UNITED STATES PATENT OFFICE.

CHRISTIAN F. HEINKEL, OF CLEVELAND, OHIO, ASSIGNOR TO THE CLEVELAND TRACTOR COMPANY, OF EUCLID, OHIO, A CORPORATION OF OHIO.

TRACK BELT.

Application filed July 22, 1920. Serial No. 398,264.

To all whom it may concern:

Be it known that I, CHRISTIAN F. HEINKEL, a citizen of the United States, residing at Cleveland, in the county of Cuyahoga and 5 State of Ohio, have invented a certain new and useful Improvement in Track Belts, of which the following is a full, clear, and exact description.

This invention is in the nature of an improvement upon the track belt which forms the subject matter of the application of Mathew B. Morgan, Serial No. 398,262 filed July 22, 1920. In the track belt shown in the said Morgan application alternate links 15 are differently shaped, which is a practical disadvantage.

The object of the present invention is to produce a track belt made up of a plurality of links which embody certain characteristics of construction disclosed in the Morgan application, but which nevertheless are exactly alike. The track belt herein shown is somewhat cheaper than that shown in the Morgan application.

25 In the drawing, Fig. 1 is a plan view of a three link section of a track belt embodying the invention. In this view portions of the top plates of the three links are broken away and the parts thereby disclosed are shown 30 in horizontal section through the axis of the pivot pins; Fig. 2 is a sectional side elevation in the plane of line 2—2 on Fig. 1, and Fig. 3 is a sectional side elevation in the plane of line 3—3 on Fig. 1; Fig. 4 is an end 35 view of one of said links; Figs. 5 and 6 are perspective views which show the so-called track members, Fig. 5 showing the closed end of one of said track members, and Fig. 6 showing the open end thereof.

40 The track belt embodying the present invention is made up of a plurality of links or units which are exactly alike. Each of these comprises a bottom plate or shoe 10, and two track members 20 secured thereon 45 by bolts 12 or other suitable means.

The two track members 20 applied to each shoe 10 are exactly alike. Each of these track members is drawn from a flat sheet metal blank into the form of a flat sided cup 50 having a closed bottom 21 and two flat sides 22, 23. When the cup-shaped track member is first drawn into shape the flat sides there-

of are connected by outwardly bent U-shaped strap loops which are then the full width of the flat sides. Thereafter the strap loops 55 are slotted as shown and a portion of each loop is bent inward, that is, toward the opposite end of the member so as to form the reversely curved straps 25. These reversely curved straps 25 are located as shown, that 60 is, at one end of the track member the reversely curved strap 25 is adjacent the closed side 21 thereof, while at the other end it is adjacent the open side thereof. Likewise, the reversely curved strap 25 at one end is 65 longitudinally aligned with and of the same width as a strap loop 24 at the other end of said member. Preferably the strap loops and straps adjacent the closed side of the track member are narrower than those at the 70 open side of said track member.

When two of these track members are applied to a bottom plate 10, to form a link, one of the flat sides 22 becomes the bottom of said member and is secured to the plate 75 10, while the other flat side 23 serves as the top of the track member. What was before the bottom of the cup now becomes the closed side 21 of the track member, and what was the open end or top of the cup becomes the 80 open side of the track member.

When two of these track members are applied to a plate 10 one of them is turned end for end with respect to the other and the closed sides 21 thereof are placed in contact 85 along the longitudinal central line of the shoe. They are then moved relatively lengthwise of the shoe to whatever extent may be necessary to bring two outwardly bent strap loops 24 on the two track members 90 into transverse alignment. At the same time the two reversely curved straps 25 at the same end of the link will also be in transverse alignment.

In order to pivotally connect two of the 95 described links, the said links are arranged in longitudinal alignment, with the strap loops 24 on one overlapping the strap loops 24 on the other,—the narrow strap loop near the longitudinal center of each link going 100 into the space between the two strap loops on the other. When the two links are in proper relation as shown a transverse eye will be formed between the overlapping

strap loops on the two links; and a pivot pin is then passed through this eye.

Attention is called to the fact that when two links have been connected as described, the ends of the strap loops on each link are in engagement with the reversely carved straps on the other. These engaging surfaces on the strap loops and straps are parts of the surface of a cylinder whose axis is coincident with the axis of the pivot pin.

In the construction shown the so-called track members not only furnish means for connecting two links together, but they furnish a track for the track wheels (which are mounted on the tractor) said track consisting of those portions of two track members which extend from their meeting sides in both directions to the slits which divide the U-shaped strap loops from the reversely curved straps. The portions 23^a of the top members so referred to, adjacent the longitudinal center of the link, are depressed below the other portions of said top members extending to the sides of the members, thereby forming a channel in which the track wheels are guided.

Having described my invention, I claim:

1. A track belt unit, comprising a shoe, and two like track members secured thereon, each track member consisting of substantially horizontal top and bottom plates and two integral straps connecting said bottom plates at each end thereof, one strap at each end being an outwardly bent strap loop and one a reversely curved strap, and each outwardly bent strap loop being in longitudinal alignment with a reversely bent strap at the other end of said member, said track members being turned end for end and being applied to the shoe on opposite sides of the longitudinal central line of said shoe and in such positions relative to each other that the straps at each end of one member are in transverse alignment with the correspondingly shaped straps on the other member.

2. A track belt unit comprising a shoe and two like track members secured thereon each track member consisting of substantially horizontal top and bottom plates and two integral straps connecting said bottom plates at each end thereof one strap at each end being an outwardly bent strap loop and one a reversely curved strap and each outwardly bent strap loop being in longitudinal alignment with a reversely bent strap loop at the other end of said member, said track members being turned end for end and being applied to the shoe on opposite sides of the longitudinal central line of said shoe and in such positions relative to each other that the straps at each end of one member are in transverse alignment with the correspondingly shaped straps on the other member, the top plates of both members adjacent the

center of the link being depressed below the remainder of said top plates thereby furnishing a longitudinally extended track wheel channel extending from one end of the link to the other.

3. A track belt comprising a plurality of pivoted together links, each of which comprises a shoe, and two like track members secured thereon, each track member consisting of substantially horizontal top and bottom plates and two integral straps connecting said plates at each end thereof, one strap at each end being an outwardly bent strap loop and one a reversely curved strap, and each outwardly bent strap loop being in longitudinal alignment with the reversely curved strap at the other end of said member,—said track members being turned end for end and being applied to the shoe on opposite sides of the longitudinal central line of said shoe and in such position relative to each other that the straps at each end of one member are in transverse alignment with the correspondingly shaped straps on the other member, said links being arranged in longitudinal alignment with the strap loops on each link overlapping the strap loops on the adjacent ends of contiguous links, and a pintle pin fitted into the eye formed by the overlapping strap loops of contiguous links.

4. A track belt comprising a plurality of pivoted together links each of which comprises a shoe, and two like track members secured thereon, each track member consisting of substantially horizontal top and bottom plates and two integral straps connecting said plates at each end thereof, one strap at each end being an outwardly bent strap loop and one a reversely curved strap and each outwardly bent strap loop being in longitudinal alignment with the reversely curved strap at the other end of said member said track members being turned end for end and being applied to the shoe on opposite sides of the longitudinal central line of said shoe and in such position relative to each other that the straps at each end of one member are in transverse alignment with the correspondingly shaped straps on the other member, said links being arranged in longitudinal alignment with the strap loops on each link overlapping the strap loops on the adjacent ends of contiguous links, and a pintle pin fitted into the eye formed by the overlapping strap loops of contiguous links, the end of each strap loop on one link being in engagement with the end of reversely curved straps on the contiguous links and the engaging surfaces of said strap loops and straps being curved on an axis coincident with the axis of the adjacent pivot pin.

5. A track belt unit for track laying tractors comprising duplicate longitudinally ex-

tending cupshaped members secured side by side with their closed sides together, said members having substantially horizontal top and bottom portions, the adjacent top portions of which provide a continuous longitudinal roller bearing surface centrally of said unit. 15

6. A track belt unit for tracklaying tractors comprising duplicate interchangeable longitudinally extending cupshaped members secured side by side with their closed sides, together, the adjacent top portions of such members being depressed to form a roller guideway and having their ends lying 10

in different longitudinal planes when assembled together. 15

7. A track belt unit for track laying tractors comprising duplicate interchangeable longitudinally extending cupshaped members secured side by side with their closed 20 sides together, said members having substantially horizontal top and bottom portions, the adjacent top portions of which provide a continuous longitudinal roller bearing surface. 25

In testimony whereof, I hereunto affix my signature.

CHRISTIAN F. HEINKEL.
